(57) **CLAIM**

I claim the ornamental design for a bait net, as shown and described.

DESCRIPTION

FIG. 1 is a perspective view of a bait net, showing my new design in an expanded configuration;

FIG. 2 is a front elevational view of FIG. 1, the rear elevational view being a mirror image thereof;

FIG. 3 is a left-side elevational view of FIG. 1, the right-side elevational view being a mirror image thereof;

FIG. 4 is a perspective view thereof in a collapsed configuration;

FIG. 5 is a front elevational view of FIG. 4;

FIG. 6 is a left-side elevational view of FIG. 4;

FIG. 7 is a rear elevational view of FIG. 4;

FIG. 8 is a right-side elevational view of FIG. 4;

FIG. 9 is a top plan view of FIG. 4; and,

FIG. 10 is a bottom plan view of FIG. 4.

The broken lines showing a tether rope in FIG. 1 depict environmental matter and form no part of the claimed design. The top and bottom plan views of both configurations are substantially identical.
